PAPER PERFORATING DEVICE

Filed March 6, 1931

UNITED STATES PATENT OFFICE

FRED J. KLINE, OF BAYVILLE, NEW YORK

PAPER PERFORATING DEVICE

Application filed March 6, 1931. Serial No. 520,602.

This invention relates to paper-perforating devices and particularly to devices of this character including a single punch which is operated by means of a lever with means for supporting the paper and for indicating the proper position thereof to permit the punching of holes therein in predetermined position.

It is the primary object of the invention to provide a simple and effective device whereby a plurality of uniformly spaced holes may be punched in the paper, the spacing being variable to meet the several requirements of standard and other binders.

Further objects and advantages of the invention will be apparent as it is better understood by reference to the following specification and accompanying drawing in which the preferred embodiments of the invention are described and illustrated. In the drawing

Fig. 1 is a plan view of a punch embodying the invention;

Fig. 2 is an enlarged sectional view on the line 2—2 of Fig. 1;

Fig. 3 is an enlarged sectional view on the line 3—3 of Fig. 1; and

Figs. 4 and 5 are plan views illustrating the manner in which the punch is used.

Referring to the drawing, the punch includes a base 5 which is preferably wider at the rear than at the front and which carries an upright support 6 at one side and at the rear thereof to provide a pivot 7 for an operating lever 8 having a knob or handle 9. The upright support 6 carries also a punch bearing 10 for a punch 11 which is connected to the lever 8. The lever is normally supported by a spring 12 mounted in the punch bearing 10. The punch 11 is generally cylindrical in form and may have an extending punch member 11' which will cut a slot in the paper from the perforation to the edge of the sheet but the lower end thereof may be of any suitable shape to conform with a corresponding opening 13 in a die plate 14 which is secured to the base 5. Thus by operating the lever 8 the punch 11 may be forced downwardly through the sheet or sheets of a paper disposed upon the base 5 and into the opening 13 to effect the perforation of the paper.

The die plate 14 is preferably marked with indicia 15, for example, in inches and fractions thereof measured from the centre line of the punch. A gauge 16 is slidably mounted in a slot 17 in the base beneath the die plate 14. The latter does not completely cover the slot and leaves an opening therefore through which an upwardly projecting finger 18 on the gauge projects. The finger 18 may be set opposite the indicia on the die plate to register the position of the left-hand edge of the sheet or sheets to be perforated so that the initial perforation therein will be at a corresponding distance from the left-hand edge of the sheet.

A gauge bar 19 is supported on the base 5 at the rear thereof to fix the position of the upper or rear edge of the sheet or sheets to be perforated. A rod 20 is supported above the gauge bar in brackets 22 and a slidably gauge 23 having a knob 24 and a shank 25 is pivotally mounted on the bar 20. The gauge bar 19 is provided with a plurality of notches 26 disposed preferably at standard distances from the centre of the punch. The standard distances between perforations for the usual types of binders are two and one-eighth inches, two and three-eighths inches, two and three-quarters inches and three and one-half inches. Of course other standards may be adopted and the notches may be disposed accordingly. The shank 25 of the gauge 23 is adapted to be disposed in one or the other of the notches, thus fixing the position of the knob 24 at a corresponding distance from and in line with the punch. Thus, when a single perforation has been formed in the paper the latter may be shifted toward the left-hand side of the device until the perforation registers with the knob 24. With the upper or rear edge of the sheet then in engagement with the gauge bar 19 the lever may be operated again to form another perforation. The distance of the second perforation from the first will depend upon the position of the gauge 26 and any number of sheets may thus be perforated with uniformly spaced openings for use in loose-leaf binders and similar devices.

The mode of operating the punch is more

clearly illustrated in Figs. 4 and 5 of the drawing in which a sheet of paper 27 is disposed with its left-hand edge 28 in engagement with the upwardly projecting finger 18.

5 The position of the finger is determined first by the length of the rear or upper edge of the sheet and the desired positioning of the perforations therein. The finger 18 being set, the first perforation will be spaced from the

10 left-hand edge of the sheet at the desired distance therefrom. When the first perforation has been made the sheet is shifted toward the left-hand edge of the device as indicated in Fig. 5 until the perforation regis-

15 ters with the knob 24. The second operation of the lever produces another perforation at a distance from the first corresponding to the previous adjustment of the gauge 23. Any successive number of perforations

20 with predetermined spacing may thus be made in the sheet by shifting it toward the left-hand side of the device and registering the last perforation made with the knob 24.

The invention as described is particularly 25 useful in perforating sheets for loose-leaf ledgers and the like. It permits the re-

quired perforation in a simple and effective manner and with assurance of uniform spacing of the perforations so that the latter will 30

register properly with the holding devices provided in the ledger or other binder. A particular advantage of the device is that it permits any desired spacing of the perforations so that it can be used to perforate

35 sheets or binders of various kinds requiring standard or other spacing of the perforations.

It will be understood that the particular 40 form of the gauges employed is not essen-

tial to the invention which depends rather upon the provision of convenient gauges arranged to permit uniform spacing of the perforations in the manner described.

45 Various changes may be made, therefore, in the details of construction and arrangement of the parts without departing from the invention or sacrificing any of the advantages thereof.

I claim:—
50 1. A punch for perforating papers comprising a base, a die and punch supported thereon, means for operating the punch, a pivoted gauge having a knob in laterally displaceable alignment with the punch and a 55 gauge bar having notches to receive and determine the position of the gauge.

2. A punch for perforating papers comprising a base, a die and punch supported thereon, means for operating the punch, a 60 gauge bar at the rear of the base, a rod supported above the gauge bar and a gauge pivoted on the rod and movable transversely of the base thereon, the gauge having means to engage a perforation in the paper.

65 3. A punch for perforating papers com-

prising a base, a die and punch supported thereon, means for operating the punch, a gauge bar at the rear of the base, a rod supported above the gauge bar and a gauge pivoted on the rod and movable transversely of 70 the base thereon, the gauge having means to engage a perforation in the paper and the gauge bar having a plurality of notches to determine the position of the gauge.

4. A punch for perforating papers comprising a base, a die and punch supported thereon, means for operating the punch, a transversely movable gauge slidably supported in the base and having a finger projecting through a slot therein and a second gauge having 80 means thereon to engage a perforation in the paper.

5. A punch for perforating papers comprising a base, a die and punch supported thereon, means for operating the punch, a 85 transversely movable gauge slidably supported in the base and having a finger projecting through a slot therein, a second gauge having means thereon to engage a perforation 90 in the paper and means to hold the second gauge in adjusted position.

6. A punch for perforating papers comprising a base, a die and punch supported thereon, means for operating the punch, a 95 transversely movable gauge slidably supported in the base and having a finger projecting through a slot therein, a second gauge having means thereon to engage a perforation in the paper means to hold the second gauge in adjusted position including a gauge 100 bar having spaced notches to receive the gauge.

In testimony whereof I affix my signature.
FRED J. KLINE.
